UNITED STATES PATENT OFFICE

GEORGES BEDARD, OF MONTREAL, QUEBEC, CANADA

CONDUCTOR TERMINAL

Application filed July 19, 1929. Serial No. 379,552.

The present invention relates to improvements in cables or other electric conductor engaging terminals.

An important object of the invention is the provision of a conductor terminal constructed so as to permit a rapid and durable connection of an electric conducting wire.

A further object of the invention is the provision of a conductor terminal designed to securely engage a conductor and to obviate the use of soldering or other connecting material.

Another object of the invention is the provision of a terminal of the above character which will be simple and durable in construction and which can be conveniently adjusted to conductor engaging position.

Other objects and advantages of the invention will become apparent as the description progresses.

In the accompanying drawings forming a part of this specification and in which like reference characters are employed to designate corresponding parts throughout the same:

Figure 1 is a perspective view of the improved terminals operatively mounted upon a supporting base and engaging an electric conductor,

Figure 2 is a fragmentary perspective view of one of the terminals prior to the connection of a conductor therewith,

Figure 3 is a similar view showing the initial connection of the terminals with a conductor,

Figure 4 is a similar view showing a successive adjustment of the terminal to wire engaging position, and

Figure 5 is an enlarged sectional view through a terminal supporting base showing one of the terminals in conductor engaging position.

Referring to the drawings, wherein for the purpose of illustration is shown a preferred embodiment of the invention, the numeral 10 generally designates a conventional form of terminal base constructed of porcelain or other insulating material, the top of the base being formed with conductor engaging

grooves and depressions adapted to receive therein the conductor securing terminals.

One portion of the base top is provided with an arcuate depression designed to support therein an arcuate, substantially horse-shoe shaped, terminal plate 11. An opposed recess in the base 10 supports a flat elongated terminal plate 12.

Each of the terminal plates 11 and 12 is provided, at its outer edge portion, with a pair of spaced arcuately bent prongs 13 turned upwardly to form conductor engaging projections. Between the prongs 13 is formed a relatively long and narrow tongue 14 spaced equidistantly between the prongs 13 and normally assuming an upwardly bent outwardly inclined position, as shown in Figures 1 and 2.

Each of the terminal plates is also provided with an interiorly threaded aperture 70 adjacent the outer edge in longitudinal alignment with the tongue 14 adapted to receive therein a terminal screw embodying a threaded shank 15 and an enlarged head 16. The head is formed with a diametrically extending groove 17 in the top thereof disposed to receive the tongue 14 in conductor engaging position. The screw head 16 is also preferably provided with spaced notches 18 for convenient turning movement thereof.

In connecting a conductor with the terminals, the insulation is removed from a portion thereof and the uncovered wire initially positioned between the bent prongs 13 and the screw, the head of the screw being positioned 85 in an elevated arrangement to receive the conductor wire thereunder. The screw is then threaded tightly upon the conductor wire and disposed so that the groove 17 will assume a longitudinal position in registration with the extension of the central tongue 14. The tongue is then bent over the wire and into the groove 17 of the terminal screw to securely clamp the conductor to obviate accidental disconnection thereof.

Thus, an extremely simple and effective terminal connection is afforded, permitting rapid connection of the conductor or removal thereof without the necessity of soldering the joint between the terminal and the conductor.

It is to be understood that the form of my invention herein shown and described is to be taken as a preferred example of the same, and that various changes as to the shape, size, and arrangement of parts may be resorted to without departing from the spirit of the invention or the scope of the subjoined claim.

Having thus described my invention, I claim:

- 10 In a conductor terminal, a terminal plate provided with a threaded aperture therethrough, a screw engageable with the aperture having an enlarged head disposed to engage a conductor between the head and the plate and provided with a diametrically extending groove in the top thereof, a pair of upwardly curved prongs extending in spaced position from the outer edge of the plate adapted to prevent outward movement of a conductor in connecting position between the screw head and the plate, and an elongated tongue projecting from the outer edge of the terminal plate between the prongs adjustable to a screw clamping position when bent over the conductor and fitted longitudinally into the groove in the screw head.
- 15
- 20
- 25

In witness whereof I have hereunto set my hand.

GEORGES BEDARD.
